Primary Examiner — Martie K Holtje*(74) Attorney, Agent, or Firm* — Banner & Witcoff, Ltd.(57) **CLAIM**

The ornamental design for a multi-state configurable bag, as shown and described.

DESCRIPTION

FIG. 1 is a perspective view of a multi-state configurable bag in a first configuration showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a perspective view of the multi-state configurable bag in a second configuration;

FIG. 8 is a front view thereof;

FIG. 9 is a rear view thereof;

FIG. 10 is a right side view thereof;

FIG. 11 is a left side view thereof; and,

FIG. 12 is a top view thereof.

The broken lines immediately adjacent to the shaded area represent unclaimed boundaries of the design. The unshaded regions form no part of the claimed design. The broken lines showing the remainder of the bag are for environmental purposes only and form no part of the claimed design.

The structural features depicted by broken lines have been shown for the purpose of illustrating portions of the multi-state configurable bag that form no part of the claimed design. It is understood that the unshaded regions form not part of the claimed design.
